UNITED STATES PATENT OFFICE.

CLINTON G. MOORE, OF MUNCIE, INDIANA.

DESIGN FOR A SPRING-MATTRESS.

45,395.

Specification for Design.

Patented Mar. 10, 1914.

Application filed December 13, 1913. Serial No. 806,640. Term of patent 14 years.

To all whom it may concern:

Be it known that I, CLINTON G. MOORE, a citizen of the United States, residing at Muncie, in the county of Delaware and State of Indiana, have invented a new, original, and ornamental Design for Spring-Mattresses, of which the following is a specification, reference being had to the accompanying drawing, forming part thereof.

Figure 1 is a plan view on a reduced scale

of a spring mattress, and Fig. 2 is an enlarged view of a portion thereof, showing my new design.

I claim:

The ornamental design for a spring mattress, as shown.

CLINTON G. MOORE.

Witnesses:

WILLIAM I. HAYMOND,

WILLIAM F. WHITE.
